ROTARY MICROFILMER

Andrew V. McClare, Fairport, N.Y., assignor to Eastman
Kodak Company, Rochester, N.Y.

Filed Apr. 2, 1973, Ser. No. 347,033

Term of patent 14 years

Int. Cl. D16—03

U.S. Cl. D61—1 Q

FIG. 1 is a top, front perspective view of a rotary microfilmer showing my new design;

FIG. 2 is a bottom, rear perspective view thereof.

I claim:

The ornamental design for a rotary microfilmer, substantially as shown.
